UNITED STATES PATENT OFFICE.

JOHANN GEISSLINGER, OF NUREMBERG, GERMANY.

SPARKING PLUG FOR EXPLOSION-MOTORS.

SPECIFICATION forming part of Letters Patent No. 745,102, dated November 24, 1903.

Application filed July 8, 1903. Serial No. 164,734. (No model.)

To all whom it may concern:

Be it known that I, JOHANN GEISSLINGER, electrical engineer, whose post-office address is No. 14 Amselstrasse, Nuremberg, Bavaria, Germany, have invented certain new and useful Improvements in a New or Improved Sparking Plug for Explosion-Motors; and I do hereby declare the following to be a full, clear, and exact description of the invention, so as will enable others skilled in the art to which it appertains to make and use the same.

My invention relates to a new or improved sparking plug for explosion-motors which has the advantage of great reliability.

15 In the sparking plugs hitherto known the central wire and binding screws were fixed to the insulating mass by means of cement or the like and were consequently liable to be loosened by the vibration of the motor. 20 In my improved plug the insulating mass is connected to the base of the plug by means of screw-threads, the connection thus being easily detachable but perfectly safe.

The so-called "spark-gap," which has hitherto been arranged outside the plug, is placed within the present plug so that perfect ignition is not prevented in case of too liberal lubrication of the motor or deposits of soot on the plug. The reliability of the motor is 30 thus considerably increased.

One form of the invention is illustrated in the annexed drawing, which is a longitudinal section of the plug.

As shown in the drawing, the lower part of 35 the porcelain block *a* is externally screw-

threaded and screwed into the base *d*. The upper part of the said block *a* is provided with a recess *b*, the wall of which is also screw-threaded. Into this recess is screwed a block *c* with a convex upper surface, and above the latter a screw or plug *h* with a conical end is 40 screwed into the said recess in such a manner that a short gap is formed between the convex and conical surfaces. The plug *h* carries the binding-screw *g*.

45 Screwed into the block *c* is the wire *f*, which extends through the foot of the plug. The wire is thus securely connected to the plug, but is easily detachable.

Asbestos washers *l* are placed between the 50 joints to prevent the escape of gas.

What I claim, and desire to secure by Letters Patent, is—

A new or improved sparking plug for explosion-motors, consisting of a base portion 55 carrying a sparking terminal, an externally-screw-threaded insulating-body screwed in said base, and provided with a recess with screw-threaded walls, a block having a terminal wire screwed thereto, threaded into 60 the bottom of said recess, and a screw-threaded block closing the recess carrying the binding-screw and separated from said block by a spark-gap.

In testimony whereof I affix my signature 65 in presence of two witnesses.

JOHANN GEISSLINGER.
